NORMAN M. MACKAY, OF WORCESTER, MASSACHUSETTS.

STABILIZER FOR LOWER DENTURES.

Application filed July 30, 1920, Serial No. 400,029. Renewed June 10, 1922. Serial No. 567,462.

To all whom it may concern:

Be it known that I, NORMAN M. MACKAY, a citizen of the United States, residing at Worcester, in the county of Worcester and 5 State of Massachusetts, have invented new and useful Improvements in Stabilizers for Lower Dentures, of which the following is a specification.

This invention relates to a stabilizer for 10 a lower denture, and the object is to overcome the tendency to looseness, common to lower sets of artificial teeth.

A further object is to provide specially shaped elements to be applied, respectively, 15 to the right and left portions of the denture directly under the eye tooth, and near the edge of the finished denture after allowing for the clearance of the muscles, for the purpose of affording the necessary restoration 20 and imparting weight and stability.

A still further object is to provide elements, located as indicated, of the proportions required for restoring the bulk thickness and additional weight natural to the 25 cuspid eminence.

A further object is to provide a plurality of elements, being curved in the manner shown and provided on the inner or concaved side with engaging devices having 30 undercut edge portions the outer or front surface including a plurality of shallow cup shaped portions which act during the natural movement of the jaw, in speaking, eating, or laughing, to impart a downward thrust, 35 throwing the denture into positive contact with the ridge of the mouth.

With the foregoing and other objects in view, the invention consists in the novel construction of the aforesaid elements and in 40 the application thereof to the denture in the manner indicated.

In the accompanying drawings:

Figure 1 is a top plan view of a lower denture, with the suction devices applied 45 thereto.

Figure 2 is a bottom plan view.

Figure 3 is a view in front elevation.

Figure 4 is a view in vertical transverse section.

50 Figure 5 is a view of one of the suction plates in elevation, and on an enlarged scale.

Figure 6 is a vertical section of the structure in Figure 5.

The denture is indicated by the reference 55 numeral 10, and the stabilizing elements are shown at 11 and 12. Each element consists of a main portion 14, curved to conform with the curvature of the element with which it is to be applied, and includes an inner en- 60 gaging device which may be of approximately the form shown at 15, this engaging device having undercut walls 16. The central portion of the element 14 projects upwardly as shown. 65

The outer surface is provided with a plurality of recessed projecting elements 18, which may be termed cup-shaped. While the cup-shaped elements have upper edge portions which protrude slightly, the edge 70 portions gradually taper toward the bottom, so that when the element is embedded, there is little or no lower ridge, rendering the cup-shaped elements effective to a maximum extent in cooperation with the muscles. 75

The elements referred to are so placed as illustrated in the drawings, that the centrally located cup-shaped element is directly under the eye tooth. They are placed low down, in order to be nearer the terminal 80 edge of the finished denture, after allowing for clearance of the muscles. The front surfaces of these devices are covered with tin foil for protection during the finishing and polishing of the denture, the foil then being 85 stripped off, and any ragged edges burnished with a blunt instrument.

The elements described are to be manufactured of the size required and formed of any suitable material, such as metal, or rubber, any substance suitable for use in the mouth, filling the requirement. 90

It is considered that the ordinary movement of the lower jaw is utilized in a novel manner, by employing these elements for 95 retaining the denture firmly in position, and that they are particularly valuable in connection with the fitting of dentures in mouths which have become shrunk and flat. The various portions of the devices described 100 are so designed and proportioned that they conform to the line of deflection of the tissues where they meet and join with the base of the ridge, the inner surfaces of the tissues overlying and being in gentle contact with 105 the cupped surfaces. Whereas the downward thrust referred to, is distinctly manifest during the movement of the jaw, when

the latter is at rest the action is lessened, and there is no continuous drawing of parts as with ordinary suction disks or the like.

Having described the invention what is claimed is:—

1. A device for the purpose specified comprising a plate, having cup shaped elements formed on its outer surface, one of said elements being at the central portion and the 10 remaining element being on opposite sides of the center, the edge portions of the cup shaped elements gradually receding downwardly.

2. A device for the purpose specified comprising a plate having curved inner and outer surfaces, the inner surface being provided with a retaining device, and the outer surface with suction devices.

3. A device for the purpose specified com-

prising a plate having a curved outer surface, and an upwardly extending portion at the central part thereof, said outer surface including a plurality of cup shaped elements forming suction devices. 20

4. In a device of the class described, a 25 denture, and a pair of elements mounted on the forward portion thereof at points spaced from the center and comprising curved plates, each provided with cup shaped elements.

5. The combination with a lower denture, 30 of suction elements embedded in the forward portion thereof at points spaced from the center and positioned opposite the cus- pids.

In testimony whereof I affix my signature.

NORMAN M. MACKAY.
